ROTARY MACHINE

Arthur J. Hodge, Lomita, and John D. Spalding,
Los Angeles, Calif., assignors, by mesne assignments,
to The National Superior Company,
Toledo, Ohio, a corporation of Delaware

Application August 12, 1933, Serial No. 684,844

5 Claims. (Cl. 255—23)

This invention relates to rotary machines as used in a rotary drilling rig when drilling for water or gas, and is more particularly related to the provision of a novel compact rotary machine 5 which is economical in construction and is particularly applicable for use in the prospecting type of drilling equipment which has for its requisites the provision of light, but yet rigid, construction.

An object of this invention is to provide a 10 novel and compact pinion shaft mounting for such a rotary machine which is economical of construction and is particularly applicable to such prospecting type of drilling equipment.

Another object of this invention is to provide a 15 rotary machine in which there is provided a novel and inexpensive form of enclosure for the gears and bearings of such rotary machine.

Another object of this invention is to provide a 20 rotary machine particularly applicable for prospecting type drilling equipment in which there is provided the novel form of bearing structure for the rotary table, including an upthrust bearing for the rotary table.

Other objects and advantages of this invention 25 is believed will be apparent from the following detailed description of a preferred embodiment thereof as illustrated in the accompanying drawings.

In the drawings:

30 Figure 1 is a top plan view of the rotary machine embodying our invention.

Figure 2 is a side elevation thereof.

Figure 3 is a sectional elevation taken substantially on the line 3—3 of Figure 1.

35 Figure 4 is a side elevation of the modified form of rotary machine embodied in our invention.

Figure 5 is a sectional side elevation of the modified form of construction shown in Figure 4.

40 Figure 6 is a fragmental sectional view illustrating the means provided for retaining the upthrust bearing means from rotation with relation to the base of the rotary machine.

In the preferred embodiment of our invention 45 as illustrated in the accompanying drawings, 1 indicates the base of a rotary machine which is provided with an annular upstanding wall 2 and an outwardly extending pinion shaft supporting portion 3. A rotary gear table 4 is rotatably supported upon the base 1 on main bearings 5 mounted within the chamber formed by the upstanding wall 2 of the base 1. The upstanding wall 2 of the base 1 is formed with an opening 6 through which a drive pinion 7 may be passed to mesh with the ring gear 8 of the rotary table 4.

55 Formed in the outer periphery of the rotary

table 4 is a groove 9 which cooperates with the upper edge of the annular wall 2 to form a labyrinth path to prevent the admission of foreign matter into the enclosure formed by the upstanding wall 2 of the base 1 and thus complete the 5 enclosure for the gears and the bearings mounted within the rotary machine base 1.

An upthrust bearing 10 is mounted below the main bearing 5 to take the upthrust which may be applied to the rotary table 4. The main bearing 5 and upthrust bearing 10 assembly is substantially identical with that disclosed in the co-pending application of David S. Faulkner, et al., Serial No. 504,758, filed December 26, 1930, Patent No. 2,005,137, issued June 18, 1935. 15

In order to lighten the structure in the manner desirable in the construction of prospecting type of drilling equipment, the table 4 is cored out as indicated at 11 in a manner well known to those skilled in the ordinary foundry practice, and 20 the gear ring 8 is mounted in position to cover the cored openings 12 leading from the cored pockets 11.

Formed in the base 1 of the rotary machine is the inner annular wall 2^a which extends upwardly in the base structure to separate the chamber in which the bearings 5 and 10 are mounted from the chamber within which the pinion 7 is mounted. The inner annular upstanding wall 2^a is likewise formed with a flange 2^b providing the thrust 25 and bearing support for the bearings 5 and 10. 30

Means are provided for driving the rotary table 4 with respect to the base 1, which means are preferably of the following construction:

A shaft 13 is mounted on the base 1 preferably in a manner to be supported at its inner end in an opening 2^c formed in the upstanding wall 2^a. The shaft 13 is supported at its outer end, or at a point spaced from the support provided at 2^c, on a cross beam 15 which is bolted as 40 indicated at 16 to the outwardly extending pinion shaft supporting portion 3 of the base 1. The pinion shaft 13 is thus supported at its inner end in the boss 14 of the inner wall 2^a within the enclosure formed by the upstanding wall 2 of the 45 base 1.

Dowels 17 are provided for accurately maintaining alignment of the cross beam shaft support with the opening 2^c in the boss 14.

The shaft 13 is shouldered at 18 and 19 to 50 position opposed bearings 20 and 21 which rotatably support a sleeve 22 upon which is integrally formed the pinion 7, sprocket 23 and lock lugs 24. A plate 25 forms a closure at the inner end of the sleeve 22 adjacent the inner bearing 20 55

and a plate 26 provides a closure for the outer end of the sleeve 22 adjacent the outer bearing 21.

In order to provide for the adjustment of the bearings 20 and 21, shims 27 are interposed between the face of the sleeve 22 and the plate 26. Cap screws 28 are provided for securing the plate 26 to the sleeve 22. In this manner the axial position of bearings 20 and 21 within the sleeve 10 22 is determined.

In order to adjust the axial position of the sleeve 22 to position this with respect to the ring gear 8, there are provided a pair of opposed threaded collars or nuts 29 which are positioned 15 on the opposite faces of the boss 30 formed on the cross beam 15. The collars 29 are screwed onto the threaded portions of the shaft 13.

To adjust the shaft axially, and hence to adjust the sleeve 22 axially, it is only necessary 20 to turn the nuts 29 the desired amount, and upon the necessary adjustment being made to tighten the nuts against the faces of the boss 30. A key 31 prevents the shaft 13 from rotating. The nuts 29 are provided with means for locking the same 25 in adjusted position, which means includes notches 32 formed in the periphery of the nuts 29 which facilitates the turning of the nuts with a spanner wrench, and which notches are also formed to receive a key 33 which is fitted within 30 an opening formed in the boss 30. The key 33 is held against movement by means of a set screw 34.

In order to hold the sleeve 22 from rotation when desired, lock pawls 35 are positioned on 35 opposite sides of the sleeve 22 in position to be engaged as desired with lock lugs 24.

In order to maintain a fluid-tight enclosure within the base 1 as formed by the upstanding wall 2, the sleeve 22 is enlarged as indicated at 40 36 to fit closely within the opening 6 formed in the wall 2 of the base 1. A stuffing box 37 is formed within the opening 6 to receive packing 38 to seal the gear and pinion enclosure. A gland 39 is employed to compress the packing 38 45 and to permit the renewal thereof as desired.

In the modified form of invention as illustrated in Figures 4, 5 and 6, the rotary machine is indicated as including a base 50 having an outer upstanding wall 51 and an outwardly extending pinion shaft supporting portion 52. A gear table 53 is rotatably mounted upon the main bearings 54 positioned within the base enclosure formed by the upstanding wall 51 of the base 50. A pinion 55 is keyed to the shaft 56 to 50 55 mesh with the ring gear 57 of the table 53. The shaft 56 is supported at its inner ends on bearings 58 supported within a boss 90' formed in the inner upstanding wall 90 of the base 50.

The outer end of the shaft 56 is supported in 60 a bearing assembly 60 mounted within a housing 61 formed integrally with a cross beam 62. The cross beam 62 is bolted to the outwardly extending portion 52 of the base 50 to secure the bearing assembly 60 in alignment with bearing 65 58. A sprocket 63 is keyed to the shaft 56 for driving the pinion 55. The sprocket 63 is formed with pockets 64 in its hub to provide stops which cooperate with lock pawls 65 for holding the pinion shaft against rotation when 70 desired.

The pinion 55 is insertable through the opening 66 formed in the wall 51 of the base 50.

In order to complete the enclosure formed by 75 the upstanding wall 51, a cover plate 67 is bolted to the outer face of the wall 51 and forms an

enclosure for the opening 66. The shaft 56 extends through the cover plate 67 and a stuffing box 68 is provided to form an oil-tight seal around the shaft 56.

In order to adjust the pinion 55 axially to 5 maintain proper meshing of the pinion 55 with the gear 57 of the rotary table, we prefer to provide the following means:

The pinion 55 is axially adjusted by axial movement of the shaft 56. The bearing assembly 60 10 consists of two opposed anti-friction bearings 69 which are designed to take the combined radial and thrust loads imposed on the outer end of the shaft 56. An adjusting nut 70 is threaded to the shaft 56 to provide the necessary adjusting means for the bearing 69. The bearing assembly 60 is axially adjustable as a unit within the housing 61 by means of shims 71 interposed between the housing 61 and the flange of the bearing sleeve 72. The removal or insertion of 20 shims 71 as desired permits of the necessary axial adjustment of the pinion 55. A cover plate 73 is provided for the end of the housing 61 to enclose the bearing units 60.

Upthrust bearing means are provided for the 25 rotary gear table, which upthrust bearing means preferably consists of an upthrust bearing ring 74 and an adjusting ring 75. The bore of the bearing ring 74 is provided with a plurality of annular grooves 76 forming a corresponding number of bearing shoulders. The lower portion of the gear table skirt 77 is also provided with a plurality of annular grooves which define annular ribs 78 that fit within the annular grooves 76 in the ring 74. The ring 74 is made of any 30 suitable bearing metal. The shoulders thus formed by the ring 74 and the table skirt 77 provide the necessary upthrust bearing area to take the loads imposed during drilling. The ring 74 is preferably split in halves which are secured 40 together by means of rivets or the like as indicated at 79, after being assembled on the skirt 77 of the table 53.

The upthrust bearing ring 74 thus forms a unit with the table 53 and is insertable into and removable from the base 50 through the opening 80 formed in the base. When the table unit, including the table 53, the main bearing 54, and the upthrust bearing 74, is assembled into the rotary base 50, it is secured against displacement by the adjustment ring 75 which is screwed onto the upthrust ring 74. The ring 75 is adjusted to retain the desired amount of bearing freedom between the bearings 54 and 74.

The ring 74 is held against rotation by means 55 of lugs 81 which engage in recesses or pockets 82 formed within the base 50. The upthrust ring 74 further provides a radial bearing for the table 53, since it is accurately aligned and fitted within the bore 80 of the base 50.

The thrust bearing surfaces between the ring 74 and the table skirt 77 are lubricated by oil which overflows from the main bearing 54. The ring 74 is formed at its upper end with the annular groove 84 to catch oil overflowing from 65 the main bearing 54 and direct the oil to the bearing surfaces formed between the ring 74 and the skirt 77.

In other respects than as herein described, the 70 modified form of rotary machine embodying our invention as shown by Figures 4, 5 and 6 is similar to that as illustrated in Figures 1, 2 and 3.

Having fully described our invention, it is to be understood that we do not wish to be limited 75

to the details herein set forth, but our invention is of the full scope of the appended claims.

We claim:

1. In a rotary machine, the combination of a base having an upstanding annular wall, a rotary gear table rotatably supported by the base and forming with the wall an enclosure, the wall having an opening, a shaft extending into the enclosure through the opening, a sleeve rotatably mounted on the shaft and extending into the opening, a pinion on one end of the sleeve within the enclosure for driving the gear table, and a drive means on the sleeve outside the enclosure for driving the pinion.
- 5 10 15 20 25 30 35 2. In a rotary machine, the combination of a base, a rotary table including a gear rotatably supported by the base, a non-rotatable shaft supported at its inner end by the base, a sleeve rotatably mounted on the shaft, said sleeve having a pinion at one end meshing with the gear on the rotary table and a sprocket at the other end for driving said sleeve, and means to support the shaft adjacent the sprocket end of the sleeve.
3. In a rotary machine, the combination of a base, a rotary table including a gear rotatably supported by the base, a shaft, means to support said shaft in non-rotative relation with said base, a sleeve rotatably mounted on the shaft, means to maintain said sleeve against axial movement relative to the shaft, said sleeve having a pinion at one end meshing with the gear on the rotary table, and a drive means at the other end for driving said sleeve, and means to axially adjust said shaft.

4. In a rotary machine, the combination of a base, a rotary table including a gear rotatably supported by the base, a shaft, means to support said shaft in non-rotative relation with the base, a sleeve rotatably mounted on the shaft, the sleeve having a pinion at one end meshing with the gear on the rotary table, a drive means at the other end for driving the sleeve and a lock means, and means mounted on the base in operative relation with the lock means on said sleeve to lock the sleeve against rotation.

5. In a rotary machine, the combination of a base having an upstanding annular wall, a gear table rotatably supported on the base, cooperating means between the upstanding wall and the table to define a labyrinth path to resist the entrance of foreign matter into the interior of the base, the wall having a cylindrical opening, a shaft, means to support the shaft on the base including a support within the enclosure defined by the upstanding annular wall of the base, a sleeve mounted on said shaft, the sleeve having a pinion insertible in the cylindrical opening and meshing with the gear on the table, a drive means at the other end for driving the sleeve, an intermediate cylindrical portion formed on the sleeve being substantially of the same diameter as the largest diameter of the pinion, and packing means between the said cylindrical portion of the sleeve and the cylindrical opening in the upstanding wall.

ARTHUR J. HODGE.
JOHN D. SPALDING.
